UNITED STATES PATENT OFFICE.

DAVID A. BROWN, OF WOODBRIDGE, NEW JERSEY.

URINAL DISINFECTANT-HOLDER.

1,130,139.

Specification of Letters Patent.

Patented Mar. 2, 1915.

Application filed November 11, 1914. Serial No. 871,500.

To all whom it may concern:

Be it known that I, DAVID A. BROWN, a citizen of the United States, residing at Woodbridge, in the county of Middlesex and 5 State of New Jersey, have invented certain new and useful Improvements in Urinal Disinfectant-Holders, of which the following is a specification.

This invention relates to urinal disinfectant holders.

More particularly, it belongs to devices constructed to hold bodies of disinfectant material, and be placed in urinals or sinks without being suspended in or attached 15 thereto.

This invention comprises a yielding spiral wire coil, having means for securing its ends together thereby forming the coil into a spiral ring constructed to contain bodies, 20 usually globular, of disinfectant material.

It is found in practice that a yielding spiral ring container for disinfectants may be knocked about in earthenware urinals during the cleaning of the urinals, or, even 25 tossed into the urinal without breaking the glazed surfaces, as would a solid and relatively hard body.

This invention furthermore comprises means for yieldingly separating the portions 30 of the coil while in ring form, for the introduction of or discharge of the disinfect-globules. It enables the holder to be charged or discharged with the globules more quickly than if the coil were not provided with 35 equivalent means for the same purpose.

The construction and arrangement of the parts of this invention are set forth in the accompanying drawings, of which—

Figure 1 represents a top plan view. Fig. 40 2 is a section of a portion of the coil on the broken line $x-x$ of Fig. 1. Fig. 3 is a section of a portion of the coil on the broken line $y-y$ of Fig. 1. Fig. 4 is a section of the lever and fulcrum members formed of 45 the wire, the section being upon the broken line $z-z$ of Fig. 1. Fig. 5 is a top plan view of the wire levers and fulcrum members, and shows the coil with its axis in a direct line.

Throughout the drawings and description, 50 the same letter is used to refer to the same part.

Considering the drawings, the spiral wire coil, which is formed of one continuous piece of wire, may be supposed, for the purposes 55 of this explanation, to have two portions marked A and α . The intermediate, double

coiled parts B and b , are usually located about midway between the ends of the coil.

In Fig. 1, the parts of the wire referred to by the letters C and c , leading from the double coils B and b , turn upwardly into outwardly-extending parts D and d , and the wire is bent to form the parts E and f . The wire is again bent upon itself to form the parts e and F, and the actual middle portion of the wire is turned upwardly into an inverted U-shaped member. The member G is the fulcrum, and it engages the bends or shoulders between the parts D and E, and d and f , as set out in Figs. 1 and 5. The loops formed by the parts E, e , and F and f of the wire, comprise the ends of two levers on the same side of the fulcrum G. The remaining legs of the levers consist of the parts D, C, B, and d , c , b , on the other side 75 of the fulcrum member G. Of the two ends of the wire coil, the end H is formed into a tapering spiral, terminated by a hook h . The other end of the wire is simply turned into a plurality of substantially annular 80 coils J.

In explaining the operation of this invention, let it be assumed that the coil, having its axis in a straight line, as indicated by the middle portion of the coil shown in Fig. 5, is bent into a ring as illustrated in Fig. 1, and the tapering spiral end H inserted in the annular terminal coils J, the hook h being engaged as shown to hold the ends together. The coil may be bent into 90 ring form even when, as is often done, it has been filled with disinfectant balls before being bent into a ring. When the axis of the coil is straight, the coil may be charged with disinfectant bodies by introducing them in the open end having the 95 annular coils J. When the coil has been so charged and bent into the ring form, the tapering end coils H passing into the coils J, prevent the escape of the disinfectant bodies. That is to say, when the coil has been bent into the ring form and the hook engaged as illustrated in Fig. 1, the open end is closed. The balls lie side by side in the coil as indicated by the broken line 105 circles K in Fig. 1. After the hook h has been engaged as shown and described, it is usually inconvenient to disengage the ends of the coil to introduce new disinfectant balls. If when it is desired to introduce 110 additional balls, the ends of the loops formed by the parts E, e , and F, f , of the

wire are pressed toward each other by the thumb and finger, the lever action upon the fulcrum member G spreads the double coils B and b apart, and the balls of disinfectant are easily passed into the coil.

Having now described this invention and explained the mode of its operation, what I claim is:

1. A urinal disinfectant holder, comprising a spiral wire coil, releasable devices for securing the ends of the coil together thereby forming the same into a spiral ring, and the said coil having connecting means whereby one portion of the coil may be separated from another portion for the introduction of disinfectant bodies.

2. A urinal disinfectant holder, comprising a ring formed of spirally coiled wire, the said spiral wire ring having double coil portions arranged next to each other, and a resilient hand-operated device connected with the said double coil portions whereby the said portions may be moved and held apart during the application of force to the said device.

3. A urinal disinfectant holder, comprising a spiral wire coil, releasable means for securing the ends of the coil thereby forming the same into a spiral ring, and means

including levers and a fulcrum formed of the wire of the coil and constructed to separate one portion of the coil from another portion thereof for the introduction of disinfectant bodies.

4. A urinal disinfectant holder, comprising a spiral wire coil having one end open, the other end having tapering coils of wire provided with a hook, the said tapering coils being constructed to enter the said open end when the coil is bent into ring form, and the said hook being arranged to engage the wire of the coil and hold the coil in ring form.

5. A urinal disinfectant holder, comprising a spiral wire coil, devices for securing the ends of the coil together thereby forming the coil into a spiral ring, and means yieldingly connecting portions of the coil whereby one portion may be separated from another portion for the introduction of disinfectant bodies.

In testimony whereof I affix my signature in presence of two witnesses.

DAVID A. BROWN.
